F. H. SPENCER

PADLOCK

Filed June 9, 1924

Inventor
Forrest H. Spencer

By Herbert E. Smith
Attorney

UNITED STATES PATENT OFFICE.

FORREST H. SPENCER, OF SPIRIT LAKE, IDAHO.

PADLOCK.

Application filed June 9, 1924. Serial No. 718,731.

To all whom it may concern:

Be it known that I, FORREST H. SPENCER, a citizen of the United States, residing at Spirit Lake, in Kootenai County and State of Idaho, have invented certain new and useful Improvements in Padlocks, of which the following is a specification.

The present invention relates to improvements in padlocks of the type generally employed for the purpose of locking spare wheels to automotive vehicles, and especially those which carry disk wheels for this purpose. The primary object of the invention is the provision of a tensioning device combined with the padlock for the purpose of preventing relative movement between the padlock and the fastening lug of the rack which carries the spare wheel, when the wheel is locked in place. By the utilization of my invention the padlock is restrained from movement with consequent rattling which would otherwise occur due to the vibrations of the traveling vehicle. A padlock so equipped is applicable for use in many other ways, but for convenience of illustration and description I have herein referred to a spare wheel as an exemplification of my invention. The purpose of my invention is accomplished by mounting a tensioning device on the lock casing between it and the hasp for engagement of the free end of the tensioning device with the fastening lug of the wheel rack which in this instance supports a spare wheel. By means of the tensioning device the padlock is held in place against movement with relation to the lug. The invention consists in certain novel combinations and arrangements of parts as will hereinafter be more fully set forth and claimed.

In the accompanying drawings I have illustrated two forms of the physical embodiment of my invention, one showing the device of the invention permanently attached to a padlock and the other illustrating the device as a removable attachment for use with standard forms of padlocks, and showing the best modes I have thus far devised for the practical application of the principles of my invention.

Figure 1 is a view showing a padlock attached to a perforated rack lug and held in horizontal position by the action of the tensioning device of my invention.

Figure 2 is an enlarged view of a padlock showing the device of my invention in section.

Figure 3 is a perspective view of the device used as a removable attachment on a padlock.

Figure 4 is an edge view of the padlock of Figs. 1 and 2 showing the hasp in section, and omitting the sliding bearing head or cup of the invention.

The device of my invention is adapted for various standard types of padlocks with U-shaped hasps, and one of these types is illustrated in the drawings where the lock casing 1 is made up of two cast plates 2 and 3 that are secured together in suitable manner. The hasp 4 is slidable and swiveled in the lock casing with its tangs 5 passing therethrough and adapted to be fastened therein for locking as usual. In Figure 1 I have shown at 6 a perforated lug which may form part of the supporting rack for a spare wheel of a vehicle, and the hasp is passed through this perforated lug for attaching the padlock thereto to prevent removal of the wheel.

The invention contemplates a cup or receptacle 7, which as shown in Figure 2 is formed by two halves cast or otherwise fashioned integral with the two plates of the lock casing and projecting from the casing between the tangs of the hasp. Each half of the cup is fashioned with a flange to provide an annular collar or flange around the end of the cup. Within the cup is located a spring 9 bearing at one end against the lock casing and at its other end against an enclosing, slide cap 10. The cup and cap are cylindrical in shape, but of course may be made in other shapes, and they are held in relative position by means of an inner annular flange or collar 11 on the hollow cap. The flange 11 encircles the cylindrical cup and permits sliding movement of the cap on the cup, while the two collars or flanges prevent displacement of the cap from the cup.

The tendency of the spring is to urge the cap away from the lock casing, but the cap may be forced to slide over the cup against tension of the spring by pressure on the cap. Thus when the hasp is being passed through the perforated rack lug, the cap is pressed and held against the lock casing to permit free-

dom of movement of the hasp. Then when the hasp is locked in position within the lock casing, the spring 9 is released and by its expansion forces the cap against the lug, 5 inside of the bend of the hasp as in Figure 1. The spring is of sufficient strength to hold the cap against the lug and push or force the lock away from the lug in such manner as to hold the bend of the hasp 10 against the perforated lug, and thus maintain the lock and hasp in rigid position with relation to the lug. In this position there is no motion permitted between the lock and its hasp and the lug, and therefore the hasp cannot rattle in the lug. The normal position of the cap, when not in use, is indicated in Figure 2 where it is shown extended and bearing against the inner side of the bend of the hasp.

15 For utilizing my invention in connection with padlocks already in use, I provide a removable attachment as shown in Figure 3. Here the spring cup 12 and its cap 13 form part of an attachment applicable for use 20 with standard types of padlocks.

The cup is provided with a pair of resilient arms 14 and 15 which form an inverted U-shape clamp. By withdrawing the slide hasp 4 and swinging one of its swiveled 25 tangs around out of the way, the spring clamp may be slipped over the lock casing 3 and is held in proper position by the frictional engagement of the resilient arms with the sides of the lock casing. The action of

the spring device of Figure 3 is the same as 35 that described with regard to Figures 1 and 2, and therefore needs no elaboration. By means of the construction of Figure 3 the device may be sold as an article of manufacture, and attached with facility to standard types of padlocks.

Having thus fully described my invention, what I claim as new and desire to secure by Letters Patent is—

1. The combination with a lock and its hasp, of a tensioning device comprising a cup integral with the lock, a relatively movable member carried by the cup, and a spring within the cup urging said member to bear against a lock support. 40

2. The combination with a lock and its hasp of a cup integral with the lock, a cap slidable on the cup and retaining means therefor, and a spring interposed between the cup and cap. 45

3. The combination with a lock and its hasp of an integral cup having an annular flange, a cap slidable on the cup and provided with a complementary retaining flange, and a spring interposed between the cup and cap. 50

4. The combination with a lock and its hasp of a flanged cup and a flanged cap, and a spring interposed between said cup and cap. 55

In testimony whereof I affix my signature.

FORREST H. SPENCER.
